ABSTRACT OF THE DISCLOSURE

Magnetic recording tape having improved stability toward storage and elevated temperatures, comprising magnetic powder which gives the tape its improved properties, the powder being a cobalt ferrite which is substituted by means of zinc, magnesium, cadmium, calcium, a mixture of zinc and magnesium, or a mixture of cadmium and calcium.

CROSS REFERENCE TO RELATED APPLICATION

This application is a continuation-in-part of our co-pending application, Ser. No. 802,031 entitled "Cobalt Ferrite Magnetic Powder for Tape Recording" filed Feb. 25, 1969, issued as U.S. Pat. No. 3,654,163 on Apr. 4, 1972.

BACKGROUND OF THE INVENTION

Field of the invention

This invention is in the field of magnetic recording powders based upon cobalt ferrite, including small amounts of zinc, magnesium, cadmium, calcium or mixtures of zinc-magnesium or cadmium-calcium as molecular substituents in the cobalt ferrite.

DESCRIPTION OF THE PRIOR ART

It has heretofore been suggested that cobalt ferrite could be used in the manufacture of magnetic recording tapes, particularly those intended to record video signals. Cobalt ferrite, per se, has a relatively high coercive force and relatively satisfactory electromagnetic conversion characteristics such as frequency response, signal to noise ratio, and the like. However, magnetic tape employing cobalt ferrite magnetic powder exhibits relatively poor storage temperature characteristics. It has been found that tapes containing cobalt ferrite after being stored at ambient temperatures or higher exhibit an undesirable attenuation of the recorded signals as compared with tapes which have not been subjected to such storage.

This disadvantage is not shared by some of the newer magnetic powders such as chromium dioxide CrO_2 . Magnetic tape made with such magnetic powders has the advantage over cobalt ferrite magnetic powders in that the former is substantially independent of storage temperature characteristics. Consequently, if the cobalt ferrite system could be modified so that it is no longer dependent upon its history of storage and temperature changes, this material would be effectively competitive with the chromium dioxide.

Cobalt ferrite compositions, per se, have been described in literature such as in Bozorth U.S. Pat. No. 2,906,979; Polasek et al. U.S. Patent No. 3,420,777; and, French Patent No. 1,129,275. However, substituted cobalt ferrites described in these patents do not have recording characteristics or storage characteristics making them suitable for use in magnetic record tapes designed primarily for the recording of video signals.

SUMMARY OF THE INVENTION

The cobalt ferrite systems of the present invention which have improved storage temperature characteristics can be represented by the following formula:

where M is zinc, magnesium, a mixture of zinc and magnesium, cadmium, calcium, or a mixture of cadmium and calcium. The numerical value of x is greater than 0.3 but less than 1, and y is greater than 0.15 but less than 0.3. The powder is in the form of single domain crystals and has a coercive force of at least 400 oersteds, preferably from 400 to 600 oersteds. One of the important features of the present invention is the fact that the ratio of saturation magnetization to coercive force (I_s/H_c) is fairly constant, the ratio at 80° C. differing from the ratio at 25° C. by no more than about 20%.

BRIEF DESCRIPTION OF THE DRAWINGS

FIG. 1 is a graph illustrating the manner in which $I_s \cdot H_c$ varies with temperature for both a cobalt ferrite and chromium dioxide;

FIG. 2 is a graph illustrating how the factor I_s/H_c varies for both materials with temperature;

FIG. 3 is a graph illustrating the manner in which I_s varies with temperature for both materials;

FIG. 4 is a graph illustrating the manner in which H_c varies with temperature for both materials; and

FIGS. 5 and 6 are plots illustrating how the molecular proportion of cobalt oxide influences other parameters.

DESCRIPTION OF THE PREFERRED EMBODIMENTS

It is generally considered that the storage temperature characteristics of the magnetic powder depend mainly upon the heat demagnetization effect, and the self-demagnetization effect.

The heat demagnetization due to temperature effects can be approximated by the equation:

$$\eta = A_0 t e \frac{H_r I_r V}{2kT} \quad (1)$$

η =heat demagnetization

A_0 =constant

t =time at which the magnetic powder is maintained at temperature T

H_c =coercive force in oersteds

I_r =residual magnetization in gauss

V =volume of one particle of magnetic powder

k =Boltzman's constant

T=temperature in °K.

e=base of natural logarithms

The demagnetization due to self-demagnetization effects can be represented by the equation:

$$\rho = f(P, W) \quad (2)$$

where

ρ =demagnetization

$P = I_r/H_c$

W =recording frequency

f =increasing function which varies with the shape of the B-H curve in the second quadrant.

Equation 1 shows that the heat demagnetization effect depends upon the residual magnetization I_r , the coercive force, H_c , and the temperature. Since I_r varies as the saturation magnetization I_s , measurement was made of the product of saturation magnetization I_s and coercive force, H_c at a temperature of T °K. with respect to a cobalt ferrite system, and chromium dioxide. The results of these measurements are shown by curves I and II in FIG. 1. From this figure, it will be seen that both curves

have similar dependence upon temperature so that both the cobalt ferrite materials and the chromium dioxide should vary in demagnetization in substantially the same way with increases in temperature.

From the fact that a magnetic tape containing chromium dioxide does not exhibit dependence on the storage temperature, and also from Equation 1 it may be presumed that the demagnetization which occurs is not due mainly to heat-demagnetization but rather to self-demagnetization as defined by Equation 2.

The coercive force, H_c of a magnetic powder having a single domain structure is given by the relationship:

$$H_c \propto \frac{K}{I_s} \quad (3)$$

Where K is termed the magnetic anisotropy constant which represents the anisotropy of magnetic internal energy per unit volume, and I_s is the saturation magnetization.

The magnetic anisotropy constant K depends upon a configurational magnetic anisotropy resulting from the anisotropy of configuration of powders and the crystalline magnetic anisotropy. In the case of chromium dioxide magnetic powder, the magnetic anisotropy constant K depends to a larger extent upon the configurational anisotropy than upon the crystalline anisotropy and is represented by the relationship:

$$K \propto I_s^2 \quad (4)$$

By substituting the expression (4) into Equation 2 it will be seen that the self-demagnetization effect depends solely upon the recording frequency W .

On the other hand, in the case of cobalt ferrite systems, the magnetic anisotropy constant K depends more completely upon the crystalline magnetic anisotropy than upon the configurational anisotropy, and is represented by the relationship:

$$K \propto e^{-ATT^2} \quad (5)$$

As will be seen from expression (3), the coercive force H_c depends upon the variation with temperature of the magnetic anisotropy constant K represented by the expression (5) and the saturation magnetization, I_s . The results obtained by measuring the relationship of I_s divided by H_c with respect to temperature in degrees centigrade is shown in FIG. 2, wherein curve I represents the results obtained in the case of a cobalt ferrite system magnetic powder, and curve II represents the results obtained in the use of chromium dioxide powder. From this figure, it will be seen that in the case of the cobalt ferrite system, the ratio I_s divided by H_c varies substantially with the temperature T , while in the case of the chromium dioxide powder, the ratio I_s over H_c remains substantially unchanged with temperature.

The variation in I_s with temperature is shown in FIG. 3. In that figure, curve I shows the results obtained by measuring I_s in terms of temperature for the cobalt ferrite system, and curve II is the same curve for the chromium dioxide system. Curve I shows that the I_s for the cobalt ferrite material remains substantially unchanged within the temperature range for the measurement.

FIG. 4 which plots the change in coercive force for the two materials in relation to temperature shows that the coercive force of the cobalt ferrite system (curve I) decreases exponentially with temperature so that the variation of coercive force with temperature corresponds to the variation of K with temperature as represented by expression (5).

The dependence of the saturation magnetization, I_s and the coercive force, H_c of the chromium dioxide powder is shown by curves II in FIGS. 3 and 4, respectively. From these figures it will be seen that the variation in coercive force with temperature is in substantial correspondence between the cobalt ferrite system and the chromium dioxide, but the former differs from the latter with

regard to their changes in I_s with temperature. Thus, it may be presumed that it is possible to obtain an improved magnetic powder with lower self-demagnetization effects and freedom from dependence on storage temperature either by minimizing the variation with temperature of the magnetic anisotropy constant K of the cobalt ferrite system to minimize the variation with temperature of the demagnetization relationship expressed in Equation 2 or by modifying the temperature characteristic of the saturation magnetization I indicated by curve I of FIG. 3 so that it corresponds to that of chromium dioxide. However, the magnetic anisotropy constant K of the cobalt ferrite system depends largely upon the crystalline anisotropy, as referred to above, and it is very difficult to change the tendency that such crystalline anisotropy changes with temperature. Therefore, the approach is to change the temperature characteristic of the saturation magnetization, I_s .

In order to change this temperature characteristic, it is necessary to add to the cobalt ferrite system, an agent which will lower the Curie point of the cobalt ferrite system to increase the I_s at low temperatures. It has been found that zinc, magnesium, a mixture of zinc and magnesium, cadmium, calcium, or a mixture of cadmium and calcium can be effectively used for this purpose. The mixtures referred to in the foregoing can contain from 10 to 90% of each of the two elements making up the mixture.

The most effective composition containing such additive agents is represented by the following formula:

where M is zinc, magnesium, a mixture of zinc and magnesium, cadmium, calcium or a mixture of cadmium and calcium. The numerical value of x is greater than 0.3 but less than 1 and y is greater than 0.15 but less than 0.3. The powder exists in the form of single domain crystals having a particle size of less than 1500 angstroms, and having a critical radius in the single domain of from 0.05 to 0.2 micron.

From FIG. 2, it will be seen that in the case of the cobalt ferrite compositions, the relationship of I_s over H_c to the temperature T can be given by:

$$T^n \propto \frac{I_s}{H_c}$$

so that n in the above expression can be used as a measure in the ratio I_s over H_c with temperature. FIG. 5 shows the results obtained by measuring the relationship between n and x with various values of y where M is either zinc or magnesium. From this figure, it will be seen that n decreases with increasing y . The decrease of n means that the variation with temperature of I_s over H_c is decreased so that x should be greater than 0.3 but less than 1, y should be greater than 0.15 for an optimum relationship to exist.

In FIG. 6, there is shown the results obtained by measuring the relationship of coercive force, H_c and x with various values of y where M is zinc or magnesium. From this figure, it will be seen that the coercive force H_c decreases with an increase of y . When y is greater than 0.3, the coercive force becomes lower than that of an ordinary magnetic tape containing gamma ferric oxide, so that the coercive force is too low to be practical. Therefore, it is desirable that the range of x with respect to coercive force H_c be such that x is greater than 0.3 but less than 1, and y should be less than 0.3.

However, where the magnetic powder is to be applied to a tape for video recording applications, the most desirable conditions are those in which x is greater than 0.3 but less than 1, and y is greater than 0.2 but less than 0.25. Under these circumstances, the material will have a coercive force, H_c ranging from about 400 to 600 oersteds.

The following specific examples illustrate methods for preparing some of the magnetic powders of the present invention, and it will be realized that the same types of syntheses can be used for producing the other materials falling within the formula given previously.

Example 1.—A first solution was prepared by dissolving 27.8 grams of ferrous sulfate ($FeSO_4 \cdot 7H_2O$) 11.95 grams of cobalt sulfate ($CoSO_4 \cdot 7H_2O$) and 2.88 grams of zinc sulfate ($ZnSO_4 \cdot 7H_2O$) in 200 cc. of water. A second solution was prepared by dissolving 14.4 grams of sodium hydroxide in 100 cc. of water. A third solution was prepared by dissolving 10.11 grams of potassium nitrate in 100 cc. of water.

The second solution was added to the first with agitation so that the mixed hydroxide of iron, cobalt, and zinc was precipitated. Then the third solution was added to the solution which contained the precipitated hydroxides, with agitation, and then the mixed solution was heated up to the boiling point for two hours. During this time, the water evaporated was replaced as required. The precipitate which resulted was rinsed and filtered. It was dried at a temperature below 100° C. The dried sample was powdered and then placed in an electric furnace and heated to a temperature of about 600° C. for two hours. The resulting product was a cobalt ferrite containing zinc as a molecular substituent.

Example 2.—In this example, the same procedure was followed as in Example 1 except that 2.48 grams of magnesium sulfate ($MgSO_4 \cdot 7H_2O$) was added instead of zinc sulfate. The product obtained was a cobalt ferrite containing magnesium as the substituent.

Example 3.—A first solution was prepared by dissolving 34.72 grams of ferrous sulfate, and 5.62 grams of cobalt sulfate, and 1.29 grams of cadmium sulfate in 200 cc. of water. A second solution was prepared by dissolving 24.0 grams of sodium hydroxide in 100 cc. of water. A third solution was prepared by dissolving 10.11 grams of potassium nitrate in 100 cc. of water. The second solution was added to the first with agitation so as to precipitate the mixed hydroxide of iron, cobalt, and cadmium. After agitation of the resulting solution, the third solution was added and agitation was continued. The resulting solution was placed in an oven for two hours. Then the resulting precipitate was rinsed and filtered and dried at a temperature below about 100° C. The dried sample was powdered and placed in an electric furnace for heat treatment at a temperature of about 400° C. for about two hours. The product which resulted was a cadmium substituted cobalt ferrite.

Example 4.—A 40% by weight aqueous solution containing 39.8 grams of ferrous chloride ($FeCl_2 \cdot 4H_2O$), 9.52 grams of cobalt chloride ($CoCl_2 \cdot 6H_2O$) and 1.47 grams of calcium chloride ($CaCl_2 \cdot 2H_2O$) was prepared and then a 6% by weight aqueous solution containing 1.5 N oxalic acid was added thereto, to form a precipitate. Then, the resulting precipitate was rinsed and dried and it was reduced with hydrogen and subsequently oxidized. The resulting product contained $\frac{1}{10}$ mol of cobalt oxide and $\frac{1}{10}$ mol of calcium oxide for every mol of ferric oxide.

Example 5.—Cobalt sulfate and zinc sulfate were added to an aqueous solution of ferric chloride of about 5% concentration to produce a mixed solution of ferric, cobalt, and zinc ions. Then an aqueous solution of about 5% sodium hydroxide concentration was added to the mixed solution to such an extent that the pH of the solution became about 12.5. This resulted in the precipitation of a mixed hydroxide of iron, cobalt and zinc. The remaining solution was heat treated at 130 to 200° C. for about thirty minutes. Then, the precipitate was filtered, dried and powdered, and placed in an electric furnace to be subjected to heat treatment at about 400° C. for two hours. The cobalt ferrite which resulted was zinc substituted.

The magnetic powders produced according to the present invention can be incorporated into suitable binders and applied on suitable base materials. Neither the composition of the binder nor the composition of the base is important for the purposes of the present invention. It is only necessary to achieve a relatively uniform distribution of the very finely divided particles into binding medium. Binders such as the various thermoplastic or thermosetting resins including polyvinyl chloride, polyvinyl chloride-acetate copolymers, cellulose acetate, polyurethane, casein, starch and all of the binders conventionally used for magnetic recording tapes can be used for the purposes of the present invention. Similarly, the composition containing the magnetic particles can be applied to any of a wide variety of bases including paper, cellulose acetate, polyethylene terephthalate (Mylar), metal foil or the like.

One of the important characteristics of the materials produced according to the present invention is their temperature stability characteristics. These characteristics were measured by applying the powders in suspension in a binding resin and coating a tape with the resulting suspension. A temperature range of 25° C. to 80° C. was employed for the tests, the upper limit being dictated by the softening temperature of typical materials used as magnetic recording bases.

It was found that the ratio of I_s to H_c for the tapes using the materials of the present invention varied less than 20% at 80° C. as compared to the same ratio at 25° C. At a temperature of 60° C., the tape coated with the particles of the present invention evidenced a decrease in the I_s/H_c ratio of 7% as compared to the ratio at 25° C., and at 80° C., the ratio was down only 15%. On the other hand, tapes coated with conventional cobalt ferrites, using the same binder and base evidenced a loss of signal level of 14% at 60° C. and 24% at 80° C., as compared to the ratio at 25° C. While these tests were made on a finished tape embodying the particles, the same results were obtained in determining the ratio of I_s to H_c with the particles.

We claim as our invention:

1. A magnetic tape comprising a base, a binder secured to said base, and magnetic powder uniformly distributed in said binder, said powder being composed of a material having the formula:

where M is selected from the group consisting of zinc, magnesium, and a mixture of zinc and magnesium, x is greater than 0.3 but less than 1, and y is greater than 0.15 but less than 0.3, said powder being in the form of single domain crystals and having a coercive force of at least 400 oersteds, said tape evidencing a ratio of I_s/H_c at 80° C. which differs from its said ratio at 25° C. by no more than 20%.

2. The magnetic tape of claim 1 in which y is greater than 0.2 but less than 0.25.

3. The magnetic tape of claim 1 in which M is zinc.

4. The magnetic tape of claim 1 in which M is magnesium.
